UNITED STATES PATENT OFFICE.

CHARLES P. STEINMETZ, OF SCHENECTADY, NEW YORK, ASSIGNOR TO GENERAL ELECTRIC COMPANY, A CORPORATION OF NEW YORK.

FILAMENT-SUPPORTS FOR INCANDESCENT LAMPS.

1,013,965.

Specification of Letters Patent.

Patented Jan. 9, 1912.

Application filed July 28, 1905. Serial No. 271,605.

To all whom it may concern:

Be it known that I, CHARLES P. STEINMETZ, a citizen of the United States, residing at Schenectady, county of Schenectady, 5 State of New York, have invented certain new and useful Improvements in Filament-Supports for Incandescent Lamps, of which the following is a specification.

In tantalum and other incandescent lamps 10 utilizing a filament which is not rigid enough at incandescent temperature to be self-supporting, it has been found convenient to mount the filament from a plurality of supports and thus prevent contact between adjacent convolutions of the filaments at all times. 15 Tantalum filaments have been found to undergo certain progressive changes affecting the mechanical structure of the filament and apparently producing globules or other enlargements along the filament separated by parts of smaller cross section. This action 20 materially contracts the filament so that it becomes tightly stretched between the rigid supports and frequently breaks when the 25 lamp is extinguished and the filament cools down.

It is the object of this invention to provide a resilient supporting means for tantalum and similar filaments whereby a considerable range of expansion and contraction is permissible without subjecting the filament to severe strains.

My invention will be better understood by reference to the drawing forming a part of 35 this specification in which,

Figure 1 is a perspective view of one modification of my improved supporting means; and Fig. 2 is a perspective view of a second modification.

40 A lamp socket 1 of ordinary form is provided with an exhausted globe 2, which if desired may be frosted. The usual hollow glass stem extends inward from the socket, and a glass part 3 projects from this stem. 45 The supporting member thus formed, sometimes termed a pedestal, carries near the base of the globe 2 a ring 4 around which a plurality of coiled springs 5 are arranged at regular intervals, and at its upper end a 50 second ring 6 provided with hooks 7 adapted to support the incandescent filament. The lead wires 8 and 9 are sealed in the glass stem at the base of the pedestal in the usual manner, and are connected to the terminals

10 and 11 of the filament. The latter is supported in a plurality of loops from the hooks 7 and at the bend at the lower end of each loop is connected one of the hooked ends of the coiled springs 5. The coiled springs are adapted to prevent displacement of the 60 loops and at the same time to permit a very considerable expansion and contraction of the filament without producing any strain sufficient to break the filament.

The modification shown in Fig. 2 embodies a somewhat different means for supporting the filament. The central pedestal 12 is provided at its top with a slightly enlarged hub 13 carrying radial arms 14 provided at their ends with hooks which support successive loops of the filament. The pedestal is also provided at its base with a second hub 15 from which radiate a plurality of coiled springs 16 provided at their outer ends with hooks to engage the lower ends of 70 the loops of the filament. It will be readily understood that by arranging the coiled springs so that the flexure is transverse to the axis of the springs the adjustment may be made very delicate and the ends of the 75 springs will pass through a considerable distance without materially increasing the 80 pull on the filament loops.

Both of the modifications above described have the further advantage of protecting 85 the filament from shocks or jars during handling as the coiled springs tend to deaden the force of such shocks and thus prevent their transmission to the filament.

What I claim as new and desire to secure 90 by Letters Patent of the United States, is,—

1. In an incandescent lamp, the combination with a fragile metal filament of a plurality of coiled springs supporting said filament at a plurality of points in its length 95 so as to permit contraction thereof.

2. In an incandescent lamp, the combination with a filament supported in a plurality of loops of resilient means for independently regulating the tension on each 100 loop of said filament.

3. In an incandescent lamp, the combination with a metal filament consisting of a plurality of loops of resilient supporting means for each of said loops acting to compensate for changes in the length thereof.

4. In an incandescent lamp, the combination of a metal filament, a plurality of sup-

ports for said filament, and a plurality of tension regulating devices engaging the filament between adjacent filament supports, each of said devices acting upon the portion 5 of the filament engaged by it independently of other portions.

5. In an incandescent lamp, the combination of a filament, a plurality of supports arranged to support said filament in a plurality of loops, and a coiled spring connected to each of said loops.

6. In an incandescent lamp, the combination of a central pedestal, a plurality of supports arranged about said pedestal, a filament held by said supports, and a plurality of springs attached to said filament at points intermediate said supports.

7. In an incandescent lamp, the combination with a metal filament comprising a plurality of loops of resilient supporting means exerting a direct pull upon each loop for protecting said filament from strains due to contraction.

8. In an incandescent lamp, the combination of a central pedestal, a plurality of supports arranged about said pedestal, a metal filament carried by said supports, and a plurality of coil springs attached to said filament to maintain it in proper position 30 on said supports.

9. In an incandescent lamp, the combination with a metal filament loop of a supporting spring engaging the bend of said loop and subject to transverse flexure from 35 the contraction of said filament loop.

10. In an incandescent lamp, the combination with a metal filament of a coiled spring engaging the filament between its ends and disposed at an angle thereto.

40 11. In an incandescent lamp, the combination with a metal filament of a coiled spring therefor subject to transverse flexure on contraction of said filament.

12. The combination with a metal filament loop, of a coiled spring engaging therewith and subject to transverse flexure on contraction of said loop.

45 13. The combination with a metal filament arranged in a loop of a coiled spring 50 engaging said loop and disposed at substantially a right angle to said loop.

14. In an incandescent lamp, the combination with a fragile metal filament loop of a relatively rigid supporting member outside 55 the plane of said loop and a resilient element projecting from said member and engaging the bend of said loop.

15. The combination of a fragile filament disposed in a loop adjacent a central pedestal and a spring projecting radially from 60 said pedestal and engaging with said loop to prevent displacement thereof.

16. The combination with a supporting member of a fragile metal filament loop having 65 its ends carried from said member, and

a resilient element secured to said supporting member and engaging the bend of said loop.

17. The combination with a fragile filament loop of a coiled spring engaging with one end thereof and subject to compression when said filament is subjected to transverse shock.

18. In an incandescent lamp, the combination of a pedestal support suitably mounted therein, a filament loop having its ends carried from said pedestal, and a resilient element extraneous to the circuit through said loop engaging the same and secured to said pedestal support, said resilient element yieldingly resisting movement of the loop in a transverse direction.

19. The combination of a supporting member, a filament arranged about said member in a plurality of loops, and a plurality of springs projecting radially from 85 said member and engaging the bends of said loops.

20. The combination of a suitable supporting member, supporting devices projecting from said member which comprise springs and suitable filament-engaging portions, and a filament arranged about said member in a plurality of loops having their bends engaged by the filament-engaging 95 portions of said supporting devices, said springs serving to maintain the filament in position and protect it from shock, and said supporting devices responding independently to variations in the length of the loops. 100

21. The combination with a plurality of adjacent filament loops of suitable supporting means engaging the bends of said filament loops and affording them yielding support, said supporting means comprising 105 springs which yieldingly resist movement of said loops toward one another.

22. The combination with a plurality of filament loops grouped about a supporting member of suitable supporting means for 110 the bends of said loops comprising supporting elements that extend transversely with reference to the filament loops and are carried from said supporting member and engage with the filament, said supporting 115 means acting upon the bends of the filament to urge them in the longitudinal direction of the loops while resiliently yielding to allow variations in the length of the loops.

23. The combination with a filament loop 120 of a supporting device for the bend of the loop comprising a spring subject to transverse flexure upon contraction of the filament and a relatively rigid supporting member lying outside the plane of the loop, the 125 part of said device engaging with the loop extending transversely with reference thereto and being carried from said supporting member.

24. The combination with a filament loop 130

of a supporting element engaging said loop and extending transversely with reference thereto, said element affording the filament resiliently yielding support and acting to keep it taut, and the part of said element engaging with the filament being free to move in the longitudinal direction of the loop with every variation in its length.

In witness whereof, I have hereunto set my hand this 27th day of July, 1905.

CHARLES P. STEINMETZ.
